UNITED STATES PATENT OFFICE.

NATHAN GOLDSMITH, OF NEWARK, NEW JERSEY.

REENFORCING ELEMENT FOR TRUNKS.

Application filed August 30, 1921. Serial No. 496,890.

To all whom it may concern:

Be it known that I, NATHAN GOLDSMITH, a citizen of the United States, and a resident of Newark, in the county of Essex and State of New Jersey, have invented new and useful Improvements in Reenforcing Elements for Trunks, of which the following is a specification.

This invention relates in general to trunks, and more particularly to reenforcing corner strips and shields and methods of applying the same to trunks or the like.

Heretofore in the manufacture of trunks the corner edge reenforcing strips have usually been of fiber and have been successively applied to the various corner edges of the trunk after which the metal corner shields have been secured in position. Thus each strip was applied separately and a great amount of time and labor was expended. Furthermore the body and cover portions of a trunk are frequently inaccurately made, that is, the corners are not square and true, and the reenforcing strips necessarily follow the inaccuracies of the trunk sides and corners so that the trunk has a rough and unfinished appearance. The strips being of fiber and the corner shields being unconnected therewith except by nails, they do not effectively resist blows on the edges of the trunk or strains incident to dropping the trunk on a corner.

The objects of the invention are to provide an improved metallic reenforcing strip for the corners and corner edges of a trunk or the like, whereby the trunk is effectively reenforced against blows on the edges thereof and strains incident to dropping the same on a corner; to provide an improved reenforcing strip comprising an angle strip of sheet metal adapted to be secured to the corner edge of a trunk; to provide a reenforcing element for trunks and the like comprising a corner shield or buffer adapted to be fitted to a trihedral corner of a trunk and having secured thereto three angle strips each adapted to fit one of the corner edges of the trunk meeting at said trihedral corner; said strips being rigidly connected to said corner shield at exactly right angles to each other; to provide such a reenforcing element the angle strips of which are of a length less than the length of the edge to which they are fitted, the free end of one of said strips being adapted to connect with the adjacent end of the strip on the same

edge carried by the next adjacent corner shield, whereby the edge reenforcing strips may be applied to the trunk simultaneously with the corner shields; to provide improved means at the valance ends of the corner strips for forming a joint between the cover portion and body portion of a trunk; to provide the reenforcing strips with improved means for longitudinally reenforcing the same and protecting the heads of the nails or rivets securing the same to the trunk against injury by sliding the trunk over a surface; to provide means for reenforcing the corners of said reenforcing strips against blows; to provide an improved method of applying reenforcing strips and corner shields to a trunk; and to obtain other results and advantages as may be brought out by the following description.

Referring to the accompanying drawings, in which like numerals of reference indicate the same parts throughout the several views, Figure 1 is a perspective view of a trunk having reenforcing elements constructed in accordance with the invention applied thereto;

Figure 2 is a detached perspective view of one of the reenforcing elements with portions broken away;

Figure 3 is a fragmentary side elevation of two of the corner edge reenforcing strips showing the manner of securing the same in a corner shield, the corner shield being shown in section;

Figure 4 is a perspective view of two of the corner strips showing the mitered ends which are joined in the corner piece;

Figure 5 is an enlarged transverse sectional view through one of the corner edge strips;

Figure 6 is a fragmentary partial plan and sectional view through one of the joint members and the abutting ends of two reenforcing strips;

Figure 7 is a perspective view of the overlapping valance ends of the reenforcing elements at the ends of the box portion and cover portion of the trunk showing the same separated;

Figure 8 is a longitudinal sectional view through the said valance ends of the strips in abutting position, and

Figure 9 is an enlarged sectional view through a modified form of the reenforcing strip.

In said drawings I have shown the inven-

tion consisting in general of a reenforcing element comprising a metal corner shield adapted to fit over the corner of a rectangular trunk or the like formed by three sides 5 meeting at substantially right angles, and three metal reenforcing strips substantially right angular in cross-section adapted to fit over the corner edges of the trunk formed by two adjacent ones of said three sides 10 meeting at right angles, said corner strips being rigidly secured to said corner shield at exactly right angles to each other. Further, when the said reenforcing element is used on a trunk, a box having a cover, or 15 the like, two of said corner strips are each formed of a length substantially equal to one-half the length of the edge to which it is applied, while the other strip is formed of a length corresponding to the depth of 20 the cover or body of the trunk as the case may be. Thus, in the application of two of said reenforcing elements to adjacent corners of a trunk, the adjacent strips of said elements meet to completely cover one edge 25 of the trunk while the other strips are applied to a portion of each of the other four edges. This construction enables the eight corners of a rectangular box or trunk and the twelve corner edges to be completely re-enforced by the application of eight of said 30 reenforcing elements, thereby reducing the time and labor required in the present methods of reenforcing trunks, ensuring a strong and rigid construction, and producing a 35 trunk having true and square covers and a thoroughly finished appearance.

In the specific embodiment of the invention shown in the drawings, the reference characters A designate the reenforcing elements 40 comprising the metal trihedral right angular corner shields 1 which are adapted to fit a corner of the trunk formed by the concurrence of three sides thereof, the said corner shields being formed with openings 45 2 to receive nails, rivets or like fastening members 3 for securing the shields to the trunk. Three corner edge reenforcing strips 4 have one end thereof rigidly secured within each of the corner shields, the said strips 50 being right angular in cross-section and arranged at exactly right angles to each other so as to fit over the corner edges of the trunk formed by two adjacent ones of three sides 55 concurring at the corner over which the corresponding corner shield A is fitted. The strips 4 may be secured in any suitable manner in the corner shield, but are preferably spot welded therein and have their ends mitered as at 5 to abut within the corner shield as shown in Figures 2 and 3. One of the strips 4 of each reenforcing element is 60 of a length substantially equal to one-half the length of the trunk, another one is of a length substantially equal to one-half of the 65 width of the trunk, and a third strip is of

a length substantially equal to the depth of the cover portion or the body portion of the trunk accordingly as the reenforcing element is applied to a corner of the cover portion or the body portion of the trunk. 70

The free end of one of the strips of each reenforcing element extending lengthwise or crosswise of the trunk, has rigidly secured thereto an angular joint member 6 which projects beyond the end of the strip and is 75 formed with openings 7 in its arms to receive nails, rivets or the like for securing the same to the trunk, while the free end of the other of said strips is adapted to fit under the joint member of the reenforcing strip on the same edge carried by the next adjacent reenforcing element. The free end of the reenforcing strip which extends depthwise of the body portion of the trunk is formed with a valance member 8 which projects beyond the end of the strip and is offset inwardly at 9, the said member being provided with openings 10 to receive rivets, 80 nails or the like. The corresponding end of the reenforcing strip which extends depthwise of the cover portion of the trunk, is formed with a cooperating valance member 11 which projects beyond the end of the reenforcing strip and is adapted to overlap the inwardly offset portion 9 of the member 8 when the cover of the trunk is closed, as 85 clearly shown in Figure 8.

In applying the reenforcing elements A to a trunk or the like, one of the elements is applied to one corner of the trunk and secured in position by means of the nails or rivets 3. Other nails or rivets 12 are then driven into the trunk through openings 13 in the reenforcing strips. A second reenforcing element is then applied to the next adjacent corner of the trunk in a similar manner, the joint member 6 of one of the reenforcing strips of said second mentioned reenforcing element overlapping the end of the reenforcing strip on the same edge carried by the first mentioned reenforcing element. This operation is continued until a reenforcing element is secured to each corner of the trunk, it being understood that the properly constructed reenforcing elements are applied respectively to the cover portion and the body portion of the trunk so that the valance members 8 and 11 will be properly arranged. The joint members 6 are preferably arranged on the strips so that the reenforcing elements can be successively applied in a right hand direction to the top side and bottom side of the trunk by merely laying the joint members of one strip over the free end of the adjacent strip, thereby eliminating the necessity of slipping the free end of one strip under the joint member of the adjacent strip except when the last reenforcing element is applied. 115

The flanges of the reenforcing strips are 120 125 130

preferably provided with longitudinal up-standing ribs 14 which reenforce the strips against bending, and the nail or rivet openings 13 are arranged adjacent the said ribs 14 so that the ribs will protect the heads of the nails or rivets against being sheared off as the trunk is drawn over a floor or the like. The corner shields 1 are also formed with angular ribs 15 which are adapted to overlie the ribs 14 of the corner edge strips. In order to reenforce the edge strips 4 against blows on the angles thereof, I may provide each of said strips with a half-round rod 16 which is rigidly secured, as by means of spot welding, to the inside of the angle of said strip, the said rod extending longitudinally of the strip substantially the full length thereof and contacting with both walls.

With this construction it will be seen that the corner shields 1 and reenforcing strips 4 being rigidly connected to each other and arranged at exactly right angles, the reenforcing elements need not conform closely to the edges of the trunk. Thus, although the edges and corners of a trunk may be inaccurate or not right angular, the reenforcing elements will impart a true and thoroughly finished appearance to the trunk. The rigid connection of the reenforcing strips 4 to the corner shields also successfully resists strains due to dropping the trunk on a corner thereof, and the ends of the reenforcing strips abutting within the corner shields and being rigidly secured thereto produce a double thickness of the material at the corner of the trunk which greatly increases the strength of the reenforcing element. Furthermore, the application of reenforcing strips and corner shields to the trunk is greatly facilitated by my invention.

The form of the invention shown and described is for the purpose of illustrating the principles of the invention only, and it will be understood that modifications can be made in the detail construction of the reenforcing elements without departing from the spirit or scope of the invention. Therefore, I do not desire to be understood as limiting myself except as required by the following claims when construed in the light of the prior art.

Having thus described the invention, what I claim is:

1. As an article of manufacture, a reenforcing element for trunks and the like, including a corner shield adapted to fit a trihedral corner of a trunk, and three corner edge strips each permanently connected at one end to said corner shield in fixed and angular relation thereto and to the other strips so that said corner shield and said edge strips may be applied simultaneously to the corner and the three corner edges formed by three concurring sides of the trunk, respectively.

2. A reenforcing element for trunks including a corner shield having angularly arranged extensions rigidly secured thereto and adapted to fit on the corner edges of a trunk, said extensions being of a length less than the length of the edges to which they are applied and adapted to abut the ends of the extensions on the same edges of similar reenforcing elements applied to adjacent corners.

3. A reenforcing strip for a corner edge of a trunk or the like, consisting of an elongated strip of sheet metal angular in cross-section to fit a corner edge of a trunk or the like and of substantially uniform thickness throughout its length, and a rod arranged in the angle of said strip extending the full length thereof and secured to both walls of the strip, said rod having its exposed side flattened to engage a corner edge of a trunk or the like.

4. A reenforcing strip for a corner edge of a trunk or the like, consisting of an elongated strip of sheet metal having two longitudinal flanges arranged at substantially right angles to each other with the angle of meeting rounded, and a half round rod secured to said strip with its rounded portion arranged within the rounded portion of said angle of the strip and its flat side exposed to engage a corner edge of a trunk or the like.

5. As an article of manufacture, a reenforcing element for trunks and the like, including a corner member, a reenforcing strip secured at one end to said corner member and extending away from the same in predetermined relation for application to a trunk, and a joint member secured to the other end of said reenforcing strip and projecting beyond the same to overlap the end of a similar reenforcing strip.

NATHAN GOLDSMITH.
